UNITED STATES PATENT OFFICE.

CHARLES E. COLEGROVE, OF EAST CLEVELAND, OHIO, ASSIGNOR TO THE WHITE SEWING MACHINE COMPANY, OF CLEVELAND, OHIO, A CORPORATION OF OHIO.

DROP-HEAD MECHANISM FOR SEWING-MACHINES.

1,272,916.

Specification of Letters Patent. Patented July 16, 1918.

Application filed April 14, 1915. Serial No. 21,436.

To all whom it may concern:

Be it known that I, CHARLES E. COLEGROVE, a citizen of the United States, residing at East Cleveland, in the county of Cuyahoga and State of Ohio, have invented a certain new and useful Improvement in Drop-Head Mechanism for Sewing-Machines, of which the following is a full, clear, and exact description.

10 This invention relates to the sort of drop leaf sewing machine cabinets which are typified by the construction shown and described in the Grothe Patent No. 799,331, dated September 12th, 1905. In fact, the improvements herein shown and described and claimed are the results of efforts made to remedy the defects which have developed during ten years of practical and commercial use of the particular construction shown 15 in said Grothe patent.

The invention consists in the construction and combination of parts shown in the drawings and hereinafter described, and pointed out definitely in the appended claims.

25 In the drawings, Figure 1 is a plan view of a sewing machine cabinet which embodies the present invention; Fig. 2 is a front elevation thereof when the parts are in the position they must occupy when the sewing machine is in use; Fig. 3 is a sectional end elevation of said cabinet showing the parts in the same position as shown in Fig. 1; Fig. 4 is a sectional view on line 4-4 in Fig. 3; Fig. 5 is an end view of the cabinet showing 30 the parts thereof in the position they will occupy normally, that is to say, when the machine is not in use; Fig. 6 is a side elevation of the said cabinet with the parts in an intermediate position.

40 The cabinet has a top or table A, a downwardly extended and immovable back member a', a front member a which is hinged along its upper edge to a part a'', which is rigid with the table. In the top there is a substantially rectangular opening a².

B represents the so-called drop leaf which is hinged along its front edge to the table top, so that when said drop leaf is in the horizontal working position, it will lie within the opening a², and this drop leaf is of such size and shape that it will substantially fill said opening.

An extension top C is hinged to the table and serves not only as an extension of the table when the machine is in working posi-

tion, but also as the lever by means of which the drop leaf may be raised to working position. A cable H is fixed to this extension leaf, passes over a part of the table and down through it in engagement with suitable guides which may be like the guides shown in Figs. 4 and 5 of said Grothe patent. The other end of this cable is made fast to an arm D which is adjustably fixed to the under side of the drop leaf near its free edge. 60

J represents a dust board which is hinged along its rear edge to the rear member a' of the cabinet, and it is under the influence of a spring J' tending to swing its free end upward. Generically, all of the parts thus far 70 described are or may be like the corresponding parts shown in said prior Grothe patent.

The arm D, as shown, is formed of two parallel sheet metal bars d³ secured together by rivets d⁴. A base plate d is fixed 75 to the under side of the drop leaf, and it has a downwardly extended arm d' whose lower end is notched on its sides to form the T-head d⁵ which is shown in Fig. 4. The rear ends of the bars d³ are notched on their under side, and they straddle this bar d' so that their notches lie over and engage the T-shaped end d⁵ thereof. A threaded rod E fixed to the plate d extends downward between the two side bars d³ of this lever; and the nuts e—e' on this threaded rod engage 80 respectively with the upper and lower sides of these bars, and thereby the lever D is adjustably fixed in position. A roller d⁶ lies 85 between these two bars d³ and is rotatably mounted thereon.

N represents a link having a pivoted connection with the rear side of the front cabinet member a near the lower edge thereof. This link is curved as shown, and its other 95 end is pivotally connected with an ear m which is a part of a bracket plate M. This bracket plate embraces the vertical part d' in which there is a vertical slot d⁷; and the screw M' which passes through this slot 100 screws into the bracket plate M and thereby the bracket plate may be fixed to said arm d'. This construction is of considerable advantage in the assembling of the parts, because when the drop leaf is down as far as it will go, the front cabinet member a should stand in the true vertical position; and it would require considerable skill and time to pivot the two ends of this link 105 to the drop leaf and front cabinet member 110

in such exact positions that this result would follow; but with the construction as shown and described, the link is permanently pivoted to the cabinet member *a*. Then when 5 the drop leaf is lowered, this member *a* is brought to the vertical position, and the bracket plate *M* allowed to take such position as it will on the part *d'*. It is then fixed in 10 that position by the screw *M'*. An arm *n* is fixed to the link *N* in substantially the position shown in Fig. 3, so that as the drop leaf is raised and lowered, a buffer block, which may be of felt or other soft material, at its end may engage the dust board. 15 In order to lower the drop leaf from its working horizontal position to its normal position the extension is swung upward and over onto the table. This slackens the cable and therefore permits the drop leaf to swing 20 downward. As its swings down the buffer *n'* secured to the end of the arm *n* will noiselessly engage the top of the dust board, and will push it down. As the drop leaf continues to descend, the roller *d''* in the 25 end of lever *D* will come into contact with this dust board, and will act upon it to push it down until it rolls off of the front edge of said dust board. The dust board will at this time be in substantial engagement with 30 the rear edge of the drop leaf, as shown in Fig. 5, and it will remain in engagement with it as long as the drop leaf remains down, thereby serving in a large measure to keep dust from the sewing machine head 35 which is fixed to the drop leaf.

To lift the drop leaf to working position, one takes hold of the extension top which at the time was lying upon the table covering the hole therein and swings it over to 40 the position shown in Figs. 1 and 2. As the drop leaf goes up the roller *d''* will engage the dust board, and will allow it to swing slowly upward under the influence of the spring *J*. As the drop leaf nears its horizontal position this roller will leave the dust 45 board. If it were not for the arm *n*, this dust board would swing upward and slap noisily against the lower edge of the hinged front member of the cabinet. Instead, however, it comes noiselessly into contact with 50 the buffer *n'*, which permits it to gradually rise until without noise it comes into contact with the lower edge of the cabinet member *A*; and it remains in contact therewith 55 until the drop leaf reaches its working position, as shown in Fig. 6.

It will be noted that the drop leaf is formed with an unbroken surface from front to rear, that is to say, it is not formed in part 60 of a hinged extension strip extending from one side to the other, as has heretofore been the common practice. When such an extension strip is used, it is necessary to provide mechanism or guides by which this extension strip is moved or guided into the open-

ing in the table and into horizontal position therein. These guides, or whatever corresponding mechanism are used, are expensive. Likewise, the extension strip is objectionable for several reasons: In the first 70 place, it presents an unsightly appearance; in the second place, the joint between it and the drop leaf furnishes a lodging place for dirt, and, finally, it prevents the rear edge of the drop leaf from helping to stop the drop 75 leaf in the horizontal position it shall occupy when the machine is ready for use. Notwithstanding all of these objections and the incidental expense, this extension piece has been used almost universally on drop leaf 80 sewing machine cabinets of the type specified.

As stated, however, the drop leaf herein shown is a jointless unbroken piece from front to rear, except that at the right hand rear corner a small rectangular piece is cut out. This is necessary because otherwise the rear edge of the drop leaf would strike the fly wheel *W'* as it swings down; and this would of course stop this down swinging 90 movement. This cut out corner is of such width and depth merely as is necessary to prevent the fly wheel from engaging the drop leaf. This cut out corner is closed by a small plate *w* hinged along its front edge 95 to the drop leaf; and normally occupying the position in which its top surface is flush with the top surface of the drop leaf; when the drop leaf is lowered this plate by engagement with the fly wheel will be swung 100 up as much as is necessary, but when the drop leaf is being raised this little plate will take its proper position as soon as it passes out of contact with said fly wheel. A spring 105 *w'* may be employed to swing this little plate to the position shown, but the action of gravity will generally be sufficient.

Cleats *Q* which are screwed to the under side of the drop leaf project rearward beyond its edge, so that when the drop leaf 110 reaches the horizontal working position these cleats will engage beneath the table top and thereby prevent any further upward movement of said drop leaf.

Having described my invention, I claim: 115

1. In a sewing machine cabinet having a table in which is an opening, the combination of a front cabinet member which is hinged along its upper edge to the table, a drop leaf hinged along its front edge to 120 the table and fitted to the said opening therein, a link pivoted at one end of said front cabinet member, a bracket to which the other end of said link is pivoted, a slotted arm fixed to and extending downward from said drop leaf, and a screw for connecting said bracket to said slotted arm.

2. In a sewing machine cabinet having a table in which is an opening, and a rigid downwardly extended back member, the com- 125

- bination of a front cabinet member which is hinged along its upper edge to the table, a drop leaf hinged along its front edge to the table and fitted to the said opening therein, 5 a link pivoted at one end to the front member and at its other end to the drop leaf, a dust board hinged along its rear edge to the rear cabinet member, a spring acting to swing said dust board upward, and an arm 10 rigidly fixed to said link and extending downwardly therefrom for engagement with said dust board.
3. In a sewing machine cabinet having a table in which is an opening, and a rigid 15 downwardly extended back member, the combination of a front cabinet member which is hinged along its upper edge to the table, a drop leaf hinged along its front edge to the table and fitted to the said opening therein, a link pivoted at one end to the front member and at its other end to the drop leaf, an arm connected to said link and extending downward therefrom for engagement with the dust board, and a dust 20 board hinged along its rear edge to the rear cabinet member, a spring acting to swing said dust board upward, a lever adjustably fixed to the under side of said drop leaf and extending forward therefrom and having at 25 its front end an anti-friction roller, which will engage said dust board as the drop leaf is swinging from one end to the other of its path of movement.
4. In a sewing machine cabinet, the combination of a table in which is a rectangular opening, a rigid drop leaf of such size and shape as to fit said hole, which drop leaf is hinged along its front edge to the table,—said drop leaf having its rear corner cut to form a notch which is in the same vertical 35 plane as the fly wheel of the sewing machine, a plate fitted to said notch and hinged along its front edge to said drop leaf whereby it will engage the fly wheel when the drop leaf is lowered, and a spring acting to return said plate to its normal position.
5. In a sewing machine cabinet having a table in which is an opening, the combination of a front cabinet member which is hinged along its upper edge to the table and 40 extends downwardly therefrom, a drop leaf hinged along its front edge to the table and fitted to the opening therein, an arm fixed to the under side of said drop leaf adjacent its rear edge, a link pivoted at one 45 end to said front member, and a bracket to which the other end of said link is pivoted, said bracket being movable upon said arm, and means to fix the bracket to said arm at any desired point in the length thereof. 50

In testimony whereof I hereunto affix my signature in the presence of two witnesses.

CHARLES E. COLEGROVE.
